UNITED STATES PATENT OFFICE.

REUBEN HITCHCOCK, OF CLEVELAND, OHIO, ASSIGNOR TO THE CLEVELAND FOLDING MACHINE COMPANY, OF CLEVELAND, OHIO, A CORPORATION OF OHIO.

FOLDING-MACHINE.

1,273,609.

Specification of Letters Patent. Patented July 23, 1918.

Application filed April 18, 1914. Serial No. 833,001.

To all whom it may concern:

Be it known that REUBEN HITCHCOCK, a citizen of the United States of America, residing at Cleveland, in the county of Cuyahoga and State of Ohio, has invented certain new and useful Improvements in Folding-Machines, of which the following is a specification.

My invention relates to improvements in folding machines, and has for its object the increase in capacity or capability of making commercial folds and generally improving the folding operations of said machines.

Said improvements are directly applicable to a type of folding machine having the general characteristics of the one set forth in the patent to Johnson, No. 893,629, granted July 21, 1908, wherein the folding operations are effected between co-acting sets of buckling and creasing rolls associated with folding plates set at an angle of 45 degrees with the vertical. A cross-feed mechanism is therein employed alternatively with a supplemental parallel-folding plate, and rolls whereby either alternating parallel and right-angle folds or three successive parallel folds may be made in the paper operated upon. Obviously, by using a deflector, two parallel folds may also be made, but it is impossible to effect a right-angle fold therewith.

My improvements are directed toward the modification of a folding machine, whereby a total of four successive parallel folds may be made either of the duplex fold or of the accordion type, prior to making the right-angle fold. It is my understanding that hitherto it has been impossible to make upon any machine, a fold of the latter description, which has distinct advantages in accomplishing smooth, even corner folds.

My improvements equally permit the formation of a less number of parallel folds prior to making the right-angle fold, and to this end, I have provided an adjustable supplemental folding frame with the folding plates horizontally positioned, which may be operated or not, as required by the particular work in hand.

Co-acting therewith is an adjustable cross-feed frame which is adapted to receive the folded sheet from two different levels in the machine and convey it to the right-angle folding rolls.

Further features of my improvements will be explained in connection with the accompanying drawings, showing sufficient of the folding machine mechanism for explaining my improvements, while omitting such features as will be understood by those skilled in the art.

Figure 1 of said drawings illustrates, in side elevation, a folding machine partially broken away and in section, to which my improvements are applicable.

Fig. 2 illustrates a front view of said machine centrally broken away and in section.

Fig. 3 is a diagrammatic vertical section of said machine whereby I may best explain the operation thereof.

Fig. 4 is a fragmentary plan view of the cross-feed mechanism.

Fig. 5 is a top view of the side plate and the mounting of its co-acting right-angle folding rolls.

Fig. 6 is a fragmentary view of the adjusting support for the cross-feed mechanism.

Fig. 7 is a view of the frame and mounting for the rolls of the supplemental parallel folding mechanism.

Fig. 8 is a diagrammatic view of the parts showing a deflector positioned before the second folding plate and the chute of the cross-feed frame in position before the second set of rolls, and

Fig. 9 is a perspective view of an accordion folded signature with a single right-angle fold, comprising twenty pages.

Throughout the several figures of the drawings, I have employed the same character of reference to indicate similar parts.

Referring first to Fig. 3, the course of the folded sheet may be traced with advantage, in forming the signature illustrated, although it is to be understood that my improved machine in common with other folding mechanisms, is adapted to be used for making a very large number of different folds, merely by suitably adjusting the members. Frame *a* mounts a feed table *b* in its upper portion, from which the unfolded sheet is delivered between rolls *b'*, *b''*, to the chute *c*, which directs it between the first pair of parallel folding rolls *d*, *e*. These serve to guide the paper into the folding plate *e'* from which the paper is

folded between rolls *e*, *f*, buckled into the folding plate *f'*, folded between the rolls *f*, *g*, buckled within the folding plate *g'*, folded between the rolls *g*, *h*, buckled within the folding plate *h'* and given its fourth parallel fold between the rolls *h*, *i*, from which it passes into the chute *i'* between slitting or creasing rolls *i''* and into the frame *j* of the cross-feed mechanism. Fig. 10 illustrates said frame and cross-feed mechanism; the latter comprising two sets of paired frusto-conical rolls *k*, suitably geared for advancing the sheet to the right along the grooved guide *k'* and between vertical buckling and creasing rolls *k''*, *l''*, associated with the co-acting side frame *l*, whereby the first right-angle fold is made. These rolls in turn pass the sheet to the left (Fig. 1) where it is engaged by a vertical bank of inclined rolls *m*, adapted to pass the sheet downward between additional folding or delivery rolls *u*, whose function need not be further explained in setting forth my particular improvements.

It will be seen that the scale of Fig. 3 is purposely increased, better to explain the operation of the machine and set forth the relation of the parts.

It will also be observed, that the parallel folding rolls are arranged in a bank or series, with their axes in two vertical rows or planes, while the feed-table and the several folding plates are in parallel arrangement and lie compactly disposed in horizontal planes. By reason of this horizontal arrangement, the paper encounters less friction in passing into and out of the folding plates, as compared with their disposition at an angle of 45 degrees, or one approaching the vertical. Moreover, the machine is more compactly built and easier of adjustment, when provided with these features.

The supplemental frame, before mentioned, is pivoted to swing the two horizontal rolls with their folding plates, out of the operative position shown, and into the dotted line position. With this adjustment of the machine, it is apparent that suitable provision must be made for conveying the paper into the cross-feed mechanism at a higher level, and to provide for this function, the frame or chute thereof may be vertically adjusted to receive the paper from between the third and fourth parallel folding rolls, or indeed at any desired level in the machine.

In making the different folds in folding machines, it is desirable to handle the paper as little as possible, in order to avoid unnecessary opportunity for creasing and wrinkling the same, hence it is better practice to dispense with a portion of the parallel folding mechanism, when less than three parallel folds are to be made. To this

end, I have provided a supplemental frame *o* which mounts the folding plates *g'*, *h'*, together with their co-acting rolls *h*, *i*, thereby permitting the removal of these members from the bank or series of rolls. 70 In furtherance of this feature, I have also made the entire frame *j*, and the cross-conveyer mechanism vertically adjustable, so that they are adapted to be elevated into position for receiving the folded sheets 75 from between the rolls *f*, *g*. This function is indicated in the diagram (Fig. 8) wherein the chute *i'* is shown in position to receive the folded sheet indicated by a curved dotted line, while a deflecting *f''* is positioned before the folding plate *f'*, in order to prevent the entrance of the folded sheet and permit the formation of a single fold between the horizontal rolls *e*, *f*.

Of course, it would be impracticable 85 briefly and adequately to set forth the various folds which can be made in a machine of this type, but after an explanation of the mechanism for effecting these folds, those skilled in the art will understand how it 90 may be adjusted to accomplish the various parallel folds required before the signature is conveyed from one level to another of the paper-folding mechanism, into the right-angle rolls.

Coming now to further explanation of the machine itself, it will be seen that the several parallel rolls, as shown in Fig. 2, are suitably geared in a bank or train to be driven in unison, of which the upper roll 100 *g* is stationarily journaled and the remaining rolls are resiliently pressed one against the other by means of spring mountings, such as are shown in Fig. 7. The first four rolls, *d*, *e*, *f* and *g*, are mounted within the 105 main frame *a* of the machine, while the frame *o* pivoted at *o'*, in said machine, serves removably to mount the rolls *h*, *i*, and their co-acting folding plates *g'*, *h'*. A resilient bar *o''*, which engages the pin 110 *a'* serves to hold the frame *o* with its rolls and folding plates in operative relation with the remaining parallel folding rolls, as shown in full lines (Fig. 3). The dotted 115 line position of these members, wherein the folding plates assume their inoperative vertical position, adapts the machine for making one or two parallel folds before the paper passes into the frame *j* of the cross-feed mechanism; this frame being elevated 120 to the distance necessary to permit chute *i'* to receive the paper from between the rolls *f*, *g*, as indicated in Fig. 8. To accomplish this, said frame *j* is afforded an upper and lower position by means of the adjustment 125 therefor, indicated in Figs. 2 and 6. This frame is provided with paired bars *j'* between which the parallel folded sheet is directed and two square supporting bars *j''*. These are laterally cut away at *j''* ad- 130

5 jacent to their lower ends to present upper and lower shoulders which engage the stationary bar p , pivotally mounted between bushings p' , inserted in the lower side frames. Straps p'' serve to clamp the rod j'' in their upper or lower positions and thereby support the frame with its chute i' disposed to receive the paper either from the rolls f , g , or the rolls h , i , of the paper 10 folding mechanism. The frusto-conical rolls k , together with their grooved guide k' , are similarly adjustable upon the bars j'' , in order to adapt the cross-conveyer mechanism to accommodate sheets of different 15 widths, as they are received from the parallel folding rolls. The full and dotted line positions of these members indicate such adjustment in Fig. 2 of the drawings, whereby a relatively short sheet or one of maximum 20 size may be conveyed to the right between vertical folding and buckling rolls k'' , l'' , associated with the side plate l . Each of the folding plates is provided with an adjustable stop or stops as e'' , g'' , 25 whereby the length of the folded sheet may be accurately determined. Similarly the side plate is provided with an adjustable longitudinal stop l^2 , which determines the length of the first right-angle fold made 30 therein.

As stated, the several rolls of the bank are resiliently pressed one against the other by means of suitable mountings interposed in the train and best shown in Fig. 7. Thus 35 the rolls h , i , are seen to be respectively journaled within pivoted end brackets q , r , which are provided with springs q' , r' , and adjusting screws q'' , r'' , for regulating the tension thereof. Roll g is shown in position of engagement therewith as the frame o is rotated 40 into operative position and secured by the bar o'' . This bar, as shown by dotted lines in Fig. 1, is likewise adapted to maintain the frame in inoperative position, when engaged with the stop a'' . In order to swing this supporting frame with its rolls and folding plates into and out of position, it is necessary to swing the cross-feed mechanism into the dotted line position, also indicated 45 in Fig. 1. This is accomplished by the pivotal mounting of said frame upon the bushings p' , shown in the lower side frames (Fig. 2) and indicated by the dotted circle (Fig. 1).

50 As shown in the top view (Fig. 5), the side plate is provided with a lateral spring l''' for supporting the paper while traveling therein, and the co-acting buckling and creasing rolls k'' , l'' and k^2 are in resilient engagement, but these features form no part of my present invention, and with other details of the folding machine, require no specific description herein.

55 While I have chosen to illustrate the twenty-page oblong book fold s of Fig. 9,

and initially describe its production in my improved folding machine, this is to be understood as illustrating merely the maximum capacity of the machine shown, for producing four successive accordion folds, 70 before the right-angle fold is made, and the same mechanism, by differently adjusting the stops in the folding plates, will produce the duplex book fold of thirty-two pages with but a single right-angle fold. 75

From the foregoing description, it will further be understood, that the displacement of the supplemental frame and the insertion of a deflector before the folding plate f' , will produce successive parallel and right-angle 80 folds in the paper s , while a deflector, similarly may be placed before the folding plates g' or h' of the supplemental frame to restrict the number of parallel folds therein.

While I have disclosed the preferred 85 means for adjusting both the supplemental frame and parallel folding rolls and plates, and correspondingly adjusting the frame of the cross-feed mechanism, I do not wish to be understood as necessarily limiting my invention to the details here embodied, nor to the precise number and arrangement of parallel folding rolls and their folding plates, except as hereinafter specified.

Having now described the preferred embodiment of my invention, I claim as new, and desire to secure by Letters Patent, the following:

1. In a folding machine, the combination with a vertically disposed bank of buckling and creasing rolls, of a set of buckling and creasing rolls positioned with their axes at an angle thereto, cross-feed mechanism adapted to convey the sheets from said vertical bank of rolls to those at an angle thereto, and means for adjusting said cross-feed mechanism, whereby the same is adapted to receive and convey the paper from different levels of said vertical bank of rolls, substantially as set forth. 110

2. In a paper-folding machine, the combination with mechanism for effecting a plurality of parallel folds, of additional mechanism for effecting a fold at an angle to said parallel folds, cross-feed mechanism for 115 transferring the folded sheets from one folding mechanism to the other, and adjusting means therefor, whereby said cross-feed mechanism is adapted to receive and convey the paper from different portions of the parallel folding mechanism, substantially as set forth. 120

3. In a folding machine, the combination with a vertically disposed bank or series of buckling and creasing rolls, of a plurality 125 of co-acting folding plates respectively associated with different sets of rolls in the series; said plates being positioned substantially horizontal and parallel to each other, whereby the folded sheets are adapted freely 130

to pass into and out of said folding plates, substantially as set forth.

4. In a folding machine, the combination with a bank or series of co-acting buckling 5 and creasing rolls arranged with their axes in two vertical rows, of means for driving the same in unison, a plurality of folding plates respectively positioned opposite different sets of rolls and upon alternate sides 10 of said bank or series; said folding plates being substantially horizontal and in planes parallel to each other, substantially as set forth.

5. In a folding machine, the combination 15 with a bank or series of co-acting buckling and creasing rolls arranged with their axes in two vertical rows, of means for driving the same in unison, a plurality of folding plates respectively positioned opposite different sets of rolls and upon alternate sides 20 of said bank or series, co-acting buckling and folding rolls positioned at an angle with those of said bank or series, cross-feed mechanism adapted to convey the folded 25 sheets from one set of rolls to the other, and a vertical adjustable means for said cross-feed mechanism adapting the same to receive and convey the sheets from different levels 30 of said bank of rolls, substantially as set forth.

6. In a folding machine, the combination with a bank or series of co-acting buckling and creasing rolls arranged with their axes in two vertical rows, of means for driving 35 the same in unison, a plurality of folding plates respectively positioned opposite different sets of rolls and upon alternate sides of said bank or series, a supplemental frame mounting a portion of said rolls and folding 40 plates, a set of rolls operating at an angle with the other, and a cross-conveying mechanism comprising a frame, adjusting means for the frame permitting it to be positioned for receiving the folded sheets either from 45 above or below the rolls in the supplemental frame, and also comprising conveying members adapted to receive and transfer the folded sheets from the bank of rolls to the set of rolls at an angle therewith, substantially as set forth.

50 7. In a folding machine, the combination with a bank or series of co-acting buckling and creasing rolls arranged with their axes in two vertical rows, of means for driving 55 the same in unison, a plurality of folding plates respectively positioned opposite different sets of rolls and upon alternate sides of said bank or series; said folding plates being substantially horizontal and in planes parallel to each other, a set of buckling and 60 creasing rolls positioned at right angles to the bank of rolls first named, and cross-conveying mechanism comprising a frame positioned approximately beneath and adjacent to the bank of rolls, adjusting means

for said frame adapting it to receive the folded sheets from different levels of said bank of rolls and also comprising conveying members adapted to pass the folded sheets between the right angle rolls, substantially 70 as set forth.

8. In a folding machine, the combination with means for advancing the sheets to be folded, of a bank or series of co-acting horizontal rolls, mechanism for rotating said 75 rolls in unison, a plurality of folding plates respectively positioned at different horizontal levels along said bank or series of rolls, a supplemental frame adjustably mounting a portion of said bank or series of rolls and 80 their co-acting folding plates as well, whereby the same may be withdrawn from operative association with the remainder of the bank, and cross-conveying mechanism adapted to receive and convey the folded 85 sheets from a level either above or below the position of the rolls in said supplemental frame, substantially as set forth.

9. In a folding machine, the combination with a bank or series of buckling and creasing rolls resiliently acting one against the other, of a plurality of folding plates horizontally positioned upon opposite sides of 90 said bank or series of rolls and respectively co-acting with different rolls of the series, 95 a supplemental frame removably mounting a portion of said rolls and their folding plates, a set of buckling and creasing rolls at right angles to, and at one side of said bank of rolls, and cross-feed mechanism, comprising transferring means adapted to receive and carry the folded sheets from the bank of rolls to the set of rolls at right angles thereto, a guide or frame for said folded sheets, and adjusting means for positioning the same to receive the sheets at a 100 level above or below the position of the rolls mounted in the supplemental frame, substantially as set forth.

10. In a folding machine, the combination 110 with a plurality of parallel-folding devices, of right-angle folding-mechanism associated therewith, a cross-conveying mechanism, and means for adjusting the same to receive and convey the signature from different 115 parallel-folding devices to said right-angle folding-mechanism, substantially as set forth.

11. In a folding machine, the combination with a plurality of parallel-folding devices, 120 of means for removably adjusting a portion of said devices in operative relation with the other devices, right-angle folding mechanism, associated with said parallel folding devices, cross-conveying mechanism, and 125 means for adjusting the same to receive and convey the signatures either from the adjustable or non-adjustable parallel folding devices to said right-angle folding mechanism, substantially as set forth.

12. In a paper folding machine, the combination with a plurality of parallel-folding appliances arranged in substantially vertical relation, of additional folding mechanism 5 for effecting a transverse fold, and adjustable intermediate conveying means for effecting the transfer of the signature and submitting it for a transverse fold in immediate succession to any parallel fold or 10 folds, substantially as set forth.

13. In a paper folding machine, the combination with a plurality of parallel-folding appliances comprising not less than three such appliances, of a co-acting transverse- 15 folding mechanism, and means for adjustably associating said transverse-folding mechanism with any desired one of the individual parallel-folding appliances, whereby a transverse fold may be effected in im-

mediate succession to any parallel fold, substantially as set forth. 20

14. In a folding machine, the combination with a plurality of stationary parallel-folding appliances, of an adjustable, parallel-folding appliance adapted to be disposed in 25 coöperative relation therewith, transverse folding mechanism and adjustable means for coöperatively associating said transverse folding mechanism alternatively with the stationary or the adjustable parallel-folding 30 appliances, substantially as set forth.

In testimony whereof I do now affix my signature in the presence of two witnesses.

REUBEN HITCHCOCK.
